UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING-MACHINE.

1,203,717.

Specification of Letters Patent. Patented Nov. 7, 1916.

Application filed August 28, 1913. Serial No. 787,047.

To all whom it may concern:

Be it known that I, JOSEPH S. DUNCAN, a citizen of the United States, residing at Chicago, in the county of Cook and State 5 of Illinois, have invented certain new and useful Improvements in Printing-Machines, of which the following is a specification.

This invention relates in general to printing machines and has more particular reference to machines of this character adapted 10 to print two or more impressions in predetermined relation upon a single web or sheet.

One of the primary objects of this invention is the provision of a machine adapted 15 for use in connection with statements, bills, work reports and the like, which customarily comprise a main sheet or body and one or more detachable stubs, each bearing printed matter common to all the reports or the 20 like, and variable printed matter which varies with each report, the purpose of the present machine being to print automatically upon a continuous web or strip of paper the printed matter common to all the reports, 25 and the variable matter which changes with each report.

Another object is the provision of mechanism which will so feed a strip of paper through the machine that the common printed 30 matter and the variable printed matter will appear upon the strip in predetermined relation, and also to provide mechanism for severing the printed strip or web, into predetermined lengths, each comprising a complete 35 report.

A further object is to provide means for perforating each report between the body portion and the stub and also between the individual stubs, if the report comprises 40 more than one stub.

Other objects and many of the attendant advantages of the invention will be apparent as the same becomes better understood, by reference to the following description when 45 considered in connection with the accompanying drawings.

Referring to the drawings Figure 1 is a plan view of a machine embodying my invention. Fig. 2 is a side elevation of the 50 machine shown in Fig. 1, certain parts being shown in sections. Fig. 3 is an enlarged end view of the impression cylinder. Fig. 4 is a detailed view of the paper severing mechanism. Fig. 5 is a fragmentary rear eleva-

tion showing the driving mechanism for the 55 paper feeding mechanism, inking rolls, etc. Fig. 6 is a face view of a report with the variable printed matter appearing thereon; Fig. 7 is a similar view of a complete report bearing the unchanging printed matter and 60 the variable printed matter. Fig. 8 is a vertical section on the line 8—8 of Fig. 1; Fig. 9 is a plan view of the duplicating mechanism, and Fig. 10 is a vertical section on the line 10—10 of Fig. 8. 65

By reference to the drawings it will be observed that the machine comprises a main frame, designated generally by reference character 11 supported upon suitable standards 12 or in any other preferred manner. 70 On top of the machine in bearings 13, 14 and 15 is mounted a longitudinally disposed main shaft 16 which may be driven by power from any suitable source, or, if preferred, may be manually operated by means of a 75 handle 17 mounted on the fly wheel 18. The various mechanisms hereinafter described are all operated from this main drive shaft.

In order that the results to be attained by this machine may be fully comprehended 80 before the details of the mechanism, which has been shown for purposes of illustration, are discussed I desire to direct attention to Figs. 6 and 7 of the drawings which illustrate diagrammatically a report which the 85 present machine is designed to produce. It is well known to those familiar with daily work reports, telephone bills, gas bills, electric light bills, statements and the like, that such reports, bills and statements comprise 90 printed matter common to all of the reports of any specific type and also variable printed matter which is different on each report and refers particularly to the individual or company to whom the report or bill is rendered 95 or designates the person or object to which the report refers. The report shown in Fig. 7 comprises a main or body portion 19 and a stub 21 capable of detachment from the body portion by reason of a score line or 100 row of perforations 22. Upon the body of the report appears printed matter 23, and the stub is likewise provided with printed matter 24, the printed matter on both the body portion and stub being common to all 105 reports of any particular species. Upon the body portion 19 and on the stub there also appears printed matter 25; this printed mat-

ter being variable and differing on each report sent out. For instance, the printed matter 23 may be in the form of a receipt which the workman signs when he receives his pay and the matter 24 may be an order signed by an officer of the company authorizing the paymaster to pay the amount indicated on the stub. The printed matter 25 may indicate the name of the workman, the 5 department in which he is working, the character of the work upon which he is engaged or any other information which, of course, varies with the individuals to whom the reports refer. It will be understood that 10 the word "report" is to be considered generically in the following description and comprehends bills, statements, vouchers and the like of various types and while I have shown on the drawings a report comprising one detachable stub it will be manifest as the invention becomes better understood that my invention contemplates the printing of reports comprising any desired number of detachable stubs.

15 25 A machine embodying my invention utilizes a web or strip 26 of paper of the required width for the reports to be printed, which strip is fed from a large roll, or, rather continuous supply, through the machine where the variable printed matter, 30 that is, the individual name and other individual information which differs on each report, is first printed on the web at predetermined intervals in such position that it will 35 appear on the body of the report and also on each stub. The web is then passed through another printing mechanism which prints the matter both on the body and on the stub which is common to all of the reports. 40 At the same time the report is perforated, or scored, between the body and the stub and also between the various stubs, if more than one stub is required, and subsequently the web is severed into predetermined 45 lengths, each of which forms a complete report.

The web, or strip of paper 26, upon which the printed matter is to be impressed is fed from a large roll or other supply (not 50 shown) in any suitable manner, and preferably the strip is positively drawn or fed from the roll by any preferred feeding mechanism which may be driven from the pulley 27 on the shaft 16. The paper passes 55 from the feeding mechanism over a guide roll 30 mounted on the main frame of the machine from whence it is fed through an intermittently operating printing mechanism which prints the variable matter thereon. 60 The details of the machine which prints this variable matter need not be specifically described in the present application as they may differ widely in their structural characteristics, one type of mechanism suitable for 65 this purpose being disclosed in my prior

Patent, No. 803,677, granted Nov. 7, 1905. The salient features of such a mechanism comprise, as shown on the drawings, a reciprocating platen 28 mounted on a frame 29 which may be raised by a spring or other suitable mechanism and which is intermittently lowered into printing position by cams 31 mounted on the shaft 16 in position to engage and depress a pair of followers 32 carried by the frame 29 and a series of 70 printing devices 33 with mechanism for positioning these devices successively in operative relation to the platen so that an impression is produced from a device on the paper at each reciprocation of the platen. 80 The printing devices, which may be of any preferred form, such, for instance, as that disclosed in my prior Patent, No. 1,026,245, granted May 14, 1912, or No. 1,015,757, granted January 23, 1912. These devices 85 are stacked in a magazine 34 at the rear of the machine from which they are successively and intermittently fed to printing position by a chain carrier 35 or other preferred means, suitable mechanism such as 90 an ink pad 36 being employed to supply each device with ink as it approaches printing position. The mechanism controlling the feeding of the printing devices is so arranged that a printing device will be retained in operative position during one or 95 more actuations of the printing platen, so that one or any desired number of impressions may be taken from one printing device before it is replaced by another. For 100 instance, if a report comprising one stub is to be printed, each printing device will be retained in printing position while the platen makes two reciprocations, thus producing one impression on the body of the 105 report and another on the stub. If a report comprises two stubs three impressions will be taken from each printing device.

The mechanism for controlling the feeding of the printing devices comprises a 110 rocker 100 pivotally mounted at 101 and provided with rollers 102 adapted to cooperate with the cams 103 on the shaft 16. The rocker 100 is connected by a link 104 to an arm secured to the rock shaft 105 to 115 which is secured an arm 106. A dog 107 is pivotally mounted at 108 on the arm 106. A spring 109 connects the lug 110 on the arm 106 to one end of the dog 107. The dog 107 is provided with an extended nose 111 and a notch 112 adapted to engage the pins 113 on the sprocket 114 about which the chain carrier 35 is disposed. As will be readily understood, when the arm 106 is rocked, the dog 107 will engage the pins 113 120 successively to rotate the sprocket 114 and advance the chain carrier.

In order that duplicate impressions may be obtained from each printing device I provide a pin 115 on the dog 107 which is 130

adapted to engage a shield 116 pivotally mounted at 117 on a member 118 which is in turn pivotally mounted at 119 on the frame of the machine. The shield 116 is 5 provided with a cut-out portion 120 which allows the pin 115 to drop therefrom as the dog 107 is retracted. A star wheel 121 is rotatably mounted at 122 and provided with a plurality of notches 123 which are alternately deep and shallow. When the pin 115 drops past the cut-out portion 120 of the shield 116 it will engage one of the notches on the star wheel 121. When a shallow notch is engaged by the pin 115 the dog 107 10 is maintained in position to engage the pin 113 on the sprocket 114 and thereby advance the sprocket chain upon forward movement of the dog. When, however, the pin 115 engages one of the deep notches 123 the nose 20 111 of the dog 107 will pass beneath the pin 113 and consequently, as the dog 107 advances, the sprocket 114 will remain stationary. Upon the succeeding movement of the dog 107 a shallow notch 123 will again 25 be engaged by the pin 115 and the resulting movement of the chain carrier 35 will advance a new printing device to printing position.

To prevent overthrow of the sprocket 114 30 an arm 124 is pivotally mounted at 125 on the frame and is normally held by a spring 126 in the position indicated in Fig. 8 in which position an abutment on the arm 124 is disposed in the path of the pins 113. The 35 end 127 of the arm 124 is disposed in the path of the arm 106 so that as the arm 106 approaches the extremity of its movement in one direction the abutment on the arm 124 will be withdrawn from the path of the 40 pins 113 and will be held in withdrawn position until the sprocket 114 has been partially rotated. As soon as the arm 124 is released the spring 126 returns it to normal position in time to engage the following 45 pin 113.

As previously stated, the member 118 is pivotally mounted at 119, the purpose being to allow the member 118 to be swung, thereby moving the shield 116 toward or 50 from the dog 107. A spring-actuated dog 128 engaging notches 129 in the end of the member 118 maintains the latter in the desired position. When the shield 116 is moved toward the dog 107 an extension 130 55 of the shield 116 is disposed in the path of the pin 115 and consequently the dog 107 is prevented from dropping into position to engage the pin 113 on the sprocket 114. Accordingly the chain conveyer 35 is not 60 advanced and a plurality of impressions may be taken from the same printing device. When the shield 116 is moved from the dog 107 the pin 115 will no longer engage the shield 116 and the chain conveyer 35 will 65 be advanced at each forward movement of

the dog 107. Consequently a fresh printing device will be disposed in printing position at each forward movement of the dog 107.

The unchanging matter may be printed on the body and stub of the report by any 70 suitable mechanism, but I prefer to utilize a rotary printing mechanism, which will now be described in a general way. In the frame 11 of the machine at one side of and in alignment with the platen 28 is mounted 75 a rotatable impression cylinder 37 equipped with plates adapted to produce the desired printed matter on the report. When a report comprising one stub is to be printed the impression cylinder is equipped as shown 80 in Fig. 3 with a plate 38 adapted to print the matter 23 on the body of the report and a plate 39 adapted to print the matter 24 on the stub. The plates, which, of course, are detachable from the cylinder, are arranged in position thereon so that the printed matter 23 and printed matter 24 appear 85 the requisite distance apart and the paper feeding mechanism, which will be later described, is timed so that the web 90 with the data 25 printed thereon at predetermined intervals is fed to the impression cylinder in such a manner that the printed matter 23 and 24 appears on the body and stub respectively of the report in pre- 95 determined position with respect to the data 25. A rotatable platen 41, preferably equal in diameter to the impression cylinder, is adapted to coöperate with said impression cylinder to effect the printing as the paper 100 passes between said cylinder and platen.

Viewing Figs. 4 and 5 it will be observed that the main drive shaft 16 is provided with a beveled pinion 42 which meshes with 105 and drives a beveled gear 43 on a transverse shaft 44 suitably mounted in the frame and provided at its outer end with a gear 45 which through the idler 46 and gear 47 on one end of the platen 41 imparts a continuous movement to the platen. The impression cylinder 37 is provided with a gear 48 equal in diameter to and meshing with gear 47, so that the impression cylinder is positively driven from the platen at the same rate of speed therewith. Any suitable ink- 110 ing mechanism may be employed to furnish ink to the plates on the plate cylinder, and I have merely shown diagrammatically, for purposes of illustration, an inking roller 49 driven from the impression cylinder through gears 51 and 52, the ink being supplied to the roller 49 from a fountain roller 53 through the ductor rollers 54 and is distributed by one or more distributing rollers 55. 115

The web of paper is directly fed to the impression cylinder by continuously operating feeding rolls 56 and 57 respectively, the roll 56 being continuously and positively driven from the plate cylinder through the 120 125

intermediary of an idler 58. Roller 57 is preferably frictionally driven from roller 56. Since the operation of the printing mechanism which prints the variable data 5 25 on the web is in the present embodiment of the invention intermittent in order that the printing devices may be changed at predetermined intervals, it is of course desirable that the paper be fed between the platen 10 and a positioned printing device by a step by step movement, so that the paper will remain stationary while an impression 25 is being made thereon but will move forward 15 between the successive actuations of the printing mechanism. With this end in view I have provided an intermittently operating paper feeding mechanism which will now be described.

Between the continuously operated paper 20 feeding mechanism and the platen 28 I have mounted a continuously driven feeding roll 59 which is driven from the roll 56 through the intermediary of an idler 61. A second roll 62, adapted to frictionally coöperate 25 with the roll 59, is mounted between the arms 63 of a bell crank lever pivoted on the main frame at 64, the other arm of this lever being equipped with a follower 66 positioned in the path of travel of an adjustable cam mounted on the end of the plate cylinder. The cam shown in the present instance is adapted to intermittently raise and lower the roll 62 at predetermined 30 intervals so that the paper web will be fed 35 forwardly intermittently the requisite distance to bring the data impressions 25 in proper position on the body and stub of the report. Preferably the cam comprises an interchangeable member 70 provided with 40 high and low portions adapted to coöperate with the follower 66. In the example shown the cam has two oppositely disposed low portions of unequal length whereby the roll 62 is allowed to engage the web and 45 intermittently and successively move it through varying distances. Adjustability of the low portions of the member 70 is provided for by the portions 67 and 67' held in position by the bolts 68 and 68' working 50 in slots 69 and 69'. The roll 62 is positively raised by the cam and is returned to operative position by means of a spring 71 fastened to the lower end of the arm 65 and to a fixed pin 72 projecting from the main 55 frame of the machine. For the purpose of guiding the paper to the intermittently operated feeding mechanism I prefer to provide a lower guide, or shelf 73, which is pivotally mounted on the frame of the machine at 74 so that its free end overlies the forward face of the roll 59 and an upper guide 75 disposed above the end of shelf 73 to engage the paper and partially retard its movement so that it will be accurately fed 60 by the feeding mechanism.

It will thus be manifest that the rolls 59 and 62 draw the paper intermittently past the platen 28 so that the data impressions 25 are produced thereon at the requisite distances apart and that the rolls 56 and 57 subsequently feed the paper to the impression cylinder by continuous movement. The continuous and intermittent feeding mechanisms are timed so that the intermittent mechanism when in operation feeds the paper 75 faster than it is fed by the continuous mechanism and the surplus paper delivered by the rolls 59 and 62 curves or folds upwardly between the continuous and intermittently operated mechanism as shown in 80 Fig. 2. When the intermittent feeding mechanism is idle during the printing operation of the platen 28 this surplus is fed by the rolls 56 and 57 to the impression cylinder. In order that the stub may be 85 readily separated from the body of the report I prefer to equip the impression cylinder 37 with a row of pins 76, as shown in Fig. 3, which form the line of perforations 90 22 between the body and the stub.

After the paper strip is printed and perforated it is desirable that it be separated into strips of desired lengths, each forming a complete report. For the purpose of dividing the web into lengths I have mounted 95 a knife on the delivery end of the machine, which will now be described. Upon the portion 77 of the main frame I have mounted a stationary blade 78, over which the paper is delivered. A knife bearing member 79 carries a shearing knife 81 adapted to coöperate with the blade 78 to sever the paper when the knife is lowered. The member 79 is pivoted on the main frame at 81 and is guided in its movements by rollers 82 and 83 movable in slots 84 and 85 respectively, formed in the frame. The knife is normally held in elevated position, as shown in Fig. 4, by a contraction spring 86 secured at one end to the member 79 and at its other end to the 100 machine frame. A bar 87 is pivoted at 88 to the member 79 and carries at its free end a roller 89 adapted to be actuated by a cam 91 mounted on the shaft 16. A link 92 serves to guide the bar 87 during its movement. The extremity of the knife 81 is guided by a knife member 93 and upper movement of the knife is limited by a stop 94 engaging with an abutment 95 on the frame. At each revolution of the shaft 16 110 the knife 81 is actuated to sever the paper, thereby producing the complete individual reports.

It is believed that my invention will be readily understood from the foregoing without further description, and while I have shown and described a preferred embodiment thereof it will be manifest that various changes in the structural details disclosed may be resorted to without departing 115 120 125 130

from the spirit of the invention or sacrificing any of the material advantages thereof.

I claim:

1. In a printing machine, the combination 5 of means for feeding a web through the machine, means for printing periodically changing data at predetermined and successively variable intervals on the web and means for subsequently printing on said web an un- 10 changing impression in predetermined relation to said first printed data.
2. In a printing machine, the combination 15 of means for feeding a strip of paper through the machine, means for printing data at predetermined and successively variable intervals on said strip, and means for subsequently printing additional data on said strip in predetermined relation to said first printed data.
- 20 3. In a printing machine, the combination of a manually operated printing platen, means for feeding printing devices into operative relation to said platen, a rotary impression cylinder, means for feeding a web intermittently and successively variable distances past said platen, and means for feeding the web continuously to said cylinder.
4. In a printing machine, the combination 30 of a reciprocatory platen mechanism for feeding printing devices successively from a stack to printing position beneath said platen, a rotary impression cylinder, means for feeding a web of material to be printed intermittently past said platen between the 35 successive operations thereof, and means for subsequently feeding said web continuously to the impression cylinder.
5. In a printing machine, the combination 40 of a platen, means for intermittently feeding printing devices into operative relation with said platen, means for operating said platen at predetermined intervals, a continuously operating printing mechanism, means for intermittently feeding a web of 45 paper or the like between said platen and a printing device between the successive operations of said platen, and means for subsequently feeding said printed strip by a continuous motion to said continuously operating printing mechanism.
6. In a printing machine, the combination 55 of a reciprocatory platen, means for successively positioning printing devices in operative relation to said platen, a rotary impression cylinder, intermittently operated paper feeding means for feeding a web of paper or the like past said platen by a step by step movement, and continuously operated paper feeding mechanism for continuously feeding said web from said intermittently operated feeding means to said rotary impression cylinder.
7. In a printing machine, the combination 65 of an intermittently operating platen, means for feeding printing devices successively to operative position with respect to said platen, a pair of paper feeding rolls, means for intermittently actuating said rolls to intermittently feed a web of paper past said platen, a continuously operating printing 70 mechanism, and continuously operated paper feeding rolls for continuously feeding paper from said intermittently actuated feeding rolls to said printing mechanism.
8. In a printing machine, the combination 75 of a reciprocatory platen, means for intermittently operating said platen, means for successively positioning data printing devices in co-operative relation to said platen, means for intermittently feeding a web of 80 paper between said platen and a printing device between the successive operations of said platen, means for subsequently printing an unchanging impression on said web in predetermined relation to the data 85 printed thereon by said platen, means for perforating said web at predetermined intervals between successive impressions, and mechanism for subsequently separating said web into lengths between successive perforations therein.
9. In a printing machine, the combination 90 of a main drive shaft, a platen intermittently actuated from said shaft, means for automatically positioning different data 95 printing devices in co-operative relation with said platen, a pair of paper feeding rolls comprising a roll mounted in stationary bearings and a roll mounted in movable bearings, means for intermittently positioning the movably mounted roll in co-operative relation with the stationarily mounted roll to intermittently feed a web past said 100 platen, a pair of continuously operating feed rolls for conveying the paper from said intermittently operating rolls, a continuously operating printing mechanism positioned to receive the paper from said continuously operating feed rolls, and means for separating the printed web into predetermined lengths.
10. In a printing machine, the combination 105 of a reciprocatory printing mechanism, paper feeding mechanism, comprising a positively driven roller and a frictionally driven roller, means for moving said frictionally driven roller intermittently into operative relation with said positively driven roller, continuously operating paper feeding mechanism adapted to feed the paper continuously from said intermittently operated mechanism, rotatable printing mechanism, a paper perforating device carried thereby, and means for severing a printed paper strip into predetermined lengths.
11. In a printing machine, the combination 115 of a main shaft, intermittently operated printing mechanism actuated by said shaft, continuously operated printing mechanism driven from said shaft, and an intermit- 120
- 125
- 130

- tently operated feeding mechanism for feeding the paper intermittently past said intermittently operated printing mechanism and comprising a continuously driven roll, a second roll mounted to move toward and from said continuously driven roll, and means for intermittently moving said second roll toward and from said continuously driven roll, and a pair of continuously operated paper feeding rolls for feeding the paper from said intermittently operated feeding mechanism to said continuously operated printing mechanism.
12. In a printing machine, the combination of an intermittently operated printing mechanism, means for intermittently feeding a strip of paper successively variable distances, a continuously operating printing mechanism comprising an impression cyl-

inder and a platen, and means operated from said impression cylinder for controlling said intermittently operative paper feeding means.

13. In a printing machine, the combination of an intermittently operated printing mechanism, continuously operated printing mechanism, means operated from said continuously operated mechanism for intermittently feeding a web of paper successively variable distances past said intermittently operated mechanism, and means for severing said printed strip of paper into predetermined lengths.

JOSEPH S. DUNCAN.
